UNITED STATES PATENT OFFICE.

WILLIAM HUGHES, OF TAUNTON, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

EYELETING-MACHINE.

1,361,863.

Specification of Letters Patent. Patented Dec. 14, 1920.

Application filed March 20, 1913, Serial No. 755,670. Renewed March 11, 1919. Serial No. 282,053.

To all whom it may concern:

Be it known that I, WILLIAM HUGHES, a citizen of the United States, residing at Taunton, in the county of Bristol and State 5 of Massachusetts, have invented certain Improvements in Eyeletting-Machines, of which the following description, in connection with the accompanying drawings, is a specification, like reference characters on the drawings indicating like parts in the several figures.

This invention relates to machines for setting fasteners such as eyelets in sheet material and one of its objects is to provide an 15 improved machine by the use of which blind or invisible eyelets may be set in the uppers of boots and shoes.

In setting invisible eyelets in a shoe upper the outer part of the upper is perforated 20 and the eyelets are set in a part of the lining, or facing stay which is stitched to the lining, in register with the holes so punched. In the finished shoe, therefore, nothing is 25 visible but a series of perforations through which the lacing passes. These perforations are relieved from the strain of the lacing and kept from pulling out of shape by the invisible eyelets set in the material directly beneath them.

30 In machines for setting blind or invisible eyelets it is customary to employ a combined punching and feeding tool to perforate both portions of the upper and then feed the upper by the punched hole. While 35 the eyelet is being set in one part of the upper the other part is pushed upwardly upon the tool where it will be out of range of the setting instrumentalities. I have discovered that it is important to limit the 40 movement of this part of the upper upon the tool, as the tool must be promptly withdrawn at the conclusion of the setting operation and its withdrawal is delayed if the part of the upper is passed upwardly upon 45 the tool farther than is necessary. An important feature of the present invention consists in means for limiting the movement upon the punching tool of the part of the upper in which the eyelet is not set.

50 As herein shown a thin separating member is employed to separate that part of the upper which is to be punched only from

that part which is to be punched and eyeleted. Another feature of the invention consists in means for supporting or reinforcing the work separating member during 55 that part of the cycle of the machine when this member would otherwise be likely to become bent or distorted. An advantage resulting from the employment of such supporting means is that the separating member 60 may take the form of a plate and may be made thinner than otherwise so that its insertion between the layers of the work is facilitated. The employment of a thin plate 65 renders it possible to locate the upsetting die and set the eyelets close up to a line of top stitching. This improves the accuracy of the work and also permits the employment 70 of the machine with less disturbance to the usual stitching room system than would be the case if it were necessary to eyelet the upper before it had been top stitched.

As herein shown the same element is 75 utilized for limiting the upward movement of the shoe upper part upon the punching and feeding tool and for supporting the work separating member, but it would be within the scope of the invention to employ 80 distinct elements for these different functions.

While the supporting and limiting means may be of any desired construction, in the illustrated embodiment of the invention, 85 their functions are supplied by a part of the presser foot. This is an advantageous construction because it utilizes parts of the machine already available, economizes space and positions the supporting means properly 90 with respect to the work separating plate. This construction, accordingly, constitutes still another feature of the invention.

These and other features of the invention will be best understood and appreciated from 95 the following description of a preferred embodiment thereof selected for purposes of illustration and shown in the accompanying drawings, in which:—

Figure 1 is a view in perspective of so 100 much of the machine as is necessary to understand its operation;

Fig. 2 is a fragmentary sectional view through the work table;

Fig. 3 is a fragmentary view in perspective of the separating plate and presser foot;

Fig. 4 shows a portion of a shoe upper having invisible eyelets set therein.

- 5 The invention is herein shown as embodied in an eyeleting machine of the type disclosed in Letters Patent of the United States No. 686,928, granted November 19, 1901. As in the machine of said patent, 10 the transversely movable head 2 carries a punch 4 which is arranged to be forced downwardly against a cutting block 6 to perforate the work and then to be moved laterally to feed the punched work into 15 alignment with the setting dies. The lower setting die 8 is arranged to pick off the lowest eyelet in a raceway and carry it upwardly inserting its barrel through the perforations in the work.
- 20 Secured to the work table 6 is a thin projecting plate 10 which carries on its lower face the upsetting die 12, the latter being disposed in alignment with the path of the lower die 8. The die carrying plate 10 is 25 made of thin material and the thickness of the die itself is reduced to a minimum, so that it may be easily inserted between two partially attached layers of sheet material, such as the lining and the outer portion of 30 a shoe upper, without disturbing their normal superposed relation. The plate is provided with a longitudinal slot 11 which extends from a point above the cutting block 6 toward, but not to, the setting position.
- 35 The die carrying plate is offset between the ends of the slot 11 so as to permit the end of the punch, when moving in the feeding operation, to pass out of the slot 11 and just clear the back of the plate. It will be 40 noted that a portion of the punch remains in the hole in the outer layer of material while the eyelet is being set in the under layer. This is advantageous because the work is thus held positively against displacement and a perfect registration of the hole with the eyelet is insured. At its extreme 45 end the plate 10 is provided with a pair of oppositely extending projections or ears 14.
- The machine is provided with a loop-shaped presser foot 16 which is rigidly secured to the upper end of a vertical rod 18 normally urged downwardly by a stiff compression spring 20 so that the presser foot is held yieldingly against the work and on 50 the table 6. Secured to the lower side of the presser foot adjacent to the setting position is a plate 17 recessed at one side or made U-shaped to accommodate the punch and disposed with its sides overlying the 55 ears 14 of the plate 10. One purpose of the plate 17 is to reinforce the die carrying plate 10 at points adjacent to the setting position, this being also the point at which the punch is retracted from the work. Another pur-

pose of the plate 17 is to limit the movement upwardly upon the punching tool of the outer portion 32 of the shoe quarter. After the setting operation the plate 10 acts as a stripper for the punch by holding down the lining and incidentally the outer portion 70 of the quarter which is stitched thereto when the punch is elevated.

A pivoted arm 22 is provided at the rear of the work table 6 and is equipped with an edge gage 23 by which the distance of 75 the eyelet from the edge of the work is determined in the usual manner. The arm 22 is connected beneath the table 6 to a hand lever 24 by which the edge gage may be swung forwardly or rearwardly to vary the 80 spread of the eyelets from the edge of the lacing slit.

In operating the machine the shoe quarter is positioned on the work table 6 with the lining 30 and attached stay, if one is used, 85 beneath the die carrying plate 10, and the outer portion 32 of the quarter above the plate 10. The point at which the first eyelet is to be set being located beneath the punch, the machine is set in operation. The 90 punch descends passing through the slot 12 and perforating both the lining and outer portion of the quarter and then moves laterally drawing the lining along the lower side of the plate 10 and the outer portion of the 95 quarter along its upper surface. The punch 4 remains in the perforation in the outer portion of the quarter throughout the feeding and setting operation but the lining is moved downwardly off the punch when it 100 encounters the downwardly bent portion of the plate 10. The feeding movement of the punch ceases when the perforation in the lining has been brought vertically above the lower setting die, the end of the punch remaining in touch with the back of the plate 10 above the upsetting die 12. At the end of its feeding movement the punch is 105 partially surrounded by a recessed plate 17. The lower die 8 is then elevated forcing the eyelet through the perforation in the lining and 110 clenching it against the upsetting die 12 while the latter is backed up by the punch reaching in through the hole in the outer part of the quarter about the same time 115 the presser foot, which has been elevated during the feeding movement, is lowered upon the work. The punch is then moved upwardly while the plate 10, which is necessarily flexible on account of its extreme thinness, is maintained in position and held against bending by the overlying plate 17 on the presser foot. The presser foot remains 120 in engagement with the work while the punch is being elevated and returned to its 125 initial position whereupon the cycle of operations may be repeated.

Having thus described my invention, I

claim as new and desire to secure by Letters Patent of the United States:

1. In an eyeleting machine, the combination of a thin projecting plate adapted to be inserted between two layers of sheet material and having an upsetting die on one face, together with a coöperating set, a punch, and means acting on said projecting plate adjacent to the die and while the punch is in the material to prevent the plate from bending.

2. In an eyeleting machine, the combination of a thin projecting plate adapted to be inserted between two layers of sheet material and having a set on one face thereof, together with means acting on said projecting plate at points on opposite sides of the set to reinforce the plate during a part of the cycle of the machine.

3. In an eyeleting machine, the combination of a thin flexible plate adapted to be inserted between the outer portion and the lining of a shoe upper and having an upsetting die on one face thereof, together with means for holding the plate against bending, comprising a member arranged to act on the plate by engaging the outer portion of the shoe upper.

4. In an eyeleting machine, the combination of a work table, a thin set-carrying plate disposed above the table, and a presser foot constructed and arranged to clamp the work against the table and also to overlie a portion of the set-carrying plate to reinforce it during a part of the cycle of the machine.

5. In an eyeleting machine, the combination of a work table, a flexible set-carrying plate disposed above the table and having laterally extending ears, and a loop-shaped presser foot having portions arranged to overlie said ears.

6. In an eyeleting machine, the combination of a work table, a flexible set-carrying plate disposed above the table and having outwardly extending portions adjacent to the set, and a reciprocatory member having a thin U-shaped plate secured thereto and arranged at its sides to overlie the outwardly extending portions of the set-carrying plate.

7. In an eyeleting machine, the combination of a thin plate adapted to be inserted between two parts of a shoe and carrying a set on one face, a punch arranged to perforate both shoe parts, said set carrying plate being so disposed with respect to the punch that it acts as a stripper therefor, and means for reinforcing said plate during the retraction of the punch.

8. In an eyeleting machine, the combination of a projecting set-supporting plate having a perforation therein, a cutting block beneath the perforation, a punch arranged to reciprocate through the perforation to

punch two parts of a shoe, one positioned on either side of the plate, and means for reinforcing the plate while the punch is being retracted.

9. A machine for inserting blind eyelets in shoe uppers, having, in combination, a punch member constructed and arranged to perforate both the leather and the lining parts of the upper, a reciprocatory eyelet carrying set, an upsetting die for clenching the eyelet barrel on the lining while a portion of the punch member remains in the hole in the leather part, and means for holding the upsetting die against displacement.

10. A machine for inserting blind eyelets in shoe uppers, having, in combination, a cutting block, a punch member movable toward the cutting block to perforate both the leather and the lining parts of the upper, an upsetting die arranged to occupy a position in the work in a plane between the leather and the lining parts when a portion of the punch member is in the leather part, a coöperating eyelet carrying set for inserting an eyelet in the lining to be clenched by the upsetting die, and means for holding the upsetting die against displacement during the retraction of the punch member.

11. A machine for inserting blind eyelets in shoe uppers, having, in combination, a tool with its end shaped for punching, said tool being movable downwardly to punch both the outer and the lining portions of a shoe upper presented in horizontal position, means for clenching the barrel of the eyelet upon the lowermost portion and independently of the uppermost portion of the upper while the tool remains in vertical line with the set and in its lowermost position, and means for limiting the movement of the outer portion of the upper upon the tool.

12. A machine for inserting blind tubular fasteners in shoe uppers comprising a plurality of layers, having, in combination, a fastener carrying set, a punch movable vertically for punching an upper presented in horizontal position and then horizontally for feeding the punched upper from a punching position at one side of the set to a position over the set, means for moving the set upwardly to insert a fastener in the lowermost layer of the upper and clench its barrel beneath the uppermost layer while the punch remains in position at the end of its feeding movement, and means for limiting the upward movement of the uppermost layer upon the punch.

13. A machine for inserting blind tubular fasteners in shoe uppers, having, in combination, a fastener carrying set, a punch constructed and arranged for punching both parts of an upper and for feeding them into position above the set, upsetting means arranged to operate coaxially with said punch

- and set in a plane between the two parts of the upper when the hole punched in the upper has been fed over the set, means for operating the set, while the parts of the upper are in this position, to set a fastener in the under part while the punch remains in its lowermost position, and means for limiting the movement of the uppermost part upon the punch.
- 10 14. In a machine for inserting blind eyelets in shoe uppers comprising outer and lining portions, the combination of a work table; an eyelet inserting set movable toward an upper supported by the table, a feeding member movable to feed a punched upper, by engagement with a hole in the upper, into line with the eyelet inserting set, means which acts, while the feeding member still controls the position of the upper, upon 15 the barrel of an eyelet inserted by the set through one portion of the upper to clench the end of the barrel upon the inner surface of said portion, and means for limiting the movement of the other portion upwardly 20 upon the feeding member.
- 15 15. A machine for setting eyelets in one of a plurality of layers of sheet material, having, in combination, a punching and feeding tool, means for limiting the movement of the upper layer of material upon the tool, and means for setting an eyelet in 25 the lower layer while the upper layer is so limited in its movement.
- 20 16. A machine for setting eyelets in one of a plurality of layers of sheet material, having, in combination, a punching and feeding tool, an upsetting die reduced in one dimension so that it may be located in concealed clenching position in a plane between 25 the layers of sheet material comprising a shoe upper, means for inserting an eyelet in the lower layer of material, while the tool occupies a position at the end of its feeding movement, and means for limiting the movement 40 of the upper layer of material upon the tool during the setting operation.
- 25 17. A machine for setting eyelets in one of a plurality of layers of sheet material, having, in combination, a punching and feeding tool, means for inserting an eyelet in one layer when the tool completes its feeding movement, and means disposed adjacent to the tool and above its end for limiting the movement of the other layer upon 45 the tool during the inserting operation.
- 30 18. In a machine for setting blind or invisible eyelets, a punch and a setting anvil capable of relative movement, means to co-operate with the punch to punch the work, means to co-operate with the anvil to insert and clench an eyelet, and means to sustain the anvil against the clenching stress, the punch being movable relatively to the latter 50 said means.
- 35 19. In a machine for setting blind or invisible eyelets, a setting anvil constructed and arranged to operate in a plane between two layers of the work, means arranged to co-operate therewith to insert and clench an eyelet, means arranged to sustain the anvil, adjacent to the axis thereof, against the clenching stress, and a punch movable relatively to the latter said means for punching a hole through the work to receive the eyelet.
- 40 20. An eyeleting machine comprising means for punching a hole through a plurality of superposed layers of work, means arranged to insert an eyelet in such hole, an upsetting die constructed and arranged to 55 clench the eyelet, conjointly with said inserting means, between two of said layers, and means other than said punching means arranged to brace the upsetting die against the upsetting stress.
- 45 21. An eyeleting machine comprising a die-supporting member constructed and arranged to extend edgewise of the work between superposed layers of the latter, an upsetting die carried by said member to operate between said layers, a setting member arranged to co-operate with said die to 60 clench an eyelet between said layers, a punch for punching a hole in the work, and means other than the punch constructed and arranged to sustain said die-supporting member, adjacent to said die, against the clenching stress.
- 50 22. An eyeleting machine comprising a work-support, a presserfoot arranged to co-operate therewith to hold the work, an eyelet-inserting member, clenching means constructed and arranged to clench an eyelet between two layers of the work, said presserfoot and said clenching means having co-operative portions arranged to sustain the latter against the clenching stress.
- 55 23. An eyeleting machine comprising means arranged to support the work, a die-supporting member constructed and arranged to extend edgewise of the work between superposed layers of the latter, a clenching die carried by said member to operate in a plane between said layers, a setting member arranged to co-operate with said die to set an eyelet in one of said layers, and means arranged to sustain the other layer of the work adjacent to said die to sustain the latter against the clenching stress.
- 60 24. An eyeleting machine comprising a die-supporting member constructed and arranged to extend edgewise of the work between superposed layers of the latter, a clenching die carried by said member to operate in a plane between said layers, a setting member arranged to co-operate with said die to set an eyelet in one of said layers, and two work-engaging members arranged

to co-act with the other layer of the work adjacent to the clenching die to sustain the latter against the clenching stress, one of said work-engaging members being movable relatively to the other and being constructed and operated to punch a hole in said other layer.

In testimony whereof I have signed my name to this specification in the presence of two subscribing witnesses.

WILLIAM HUGHES.
